APPARATUS FOR RESHAPING WORN RAILWAY TRACK IRONS

Olaf J. Nyberg, Youngstown, Ohio, assignor to
Youngstown Steel Car Corporation, a corpora-
tion of Ohio

Application November 13, 1928
Serial No. 319,165

4 Claims. (Cl. 78—76)

My invention relates to reclaiming or reshaping railway track irons or similar metal articles, and particularly worn rail splice bars or the like, and aims to improve generally existing methods and apparatus for reshaping worn rail splice bars or "fish plates", as by reforging them by an improved method so as to restore them for the purpose and service for which they were originally intended or to different shapes, as desired. The invention further aims to provide apparatus capable of economically reforging and reshaping such bars according to my improved method.

In order better to illustrate my improved method and apparatus, I have shown in the accompanying drawings one form of apparatus suitable for practicing the method and embodying principal features of the apparatus.

In the drawings:

Fig. 1 is a view partly in side elevation and partly in longitudinal section showing one form of forging apparatus suitable for reshaping worn splice bars;

Fig. 2 is a vertical sectional view taken on the line 2—2 of Fig. 1 showing the bar in position between the dies before the reforming operation is commenced;

Fig. 3 is a similar view taken on the line 3—3 of Fig. 1, showing the bar in position after the reforging operation; and

Fig. 4 is a side elevation of a conventional form of splice bar.

The splice bars or "fish plates", as they are termed, may be of any conventional design, and, as is common, are provided with bolt holes extending transversely through the web portion of the bar. As is customary, the bolt holes in each bar are alternately round and elliptical (see Fig. 4)—so that when a pair of bars are in position on opposite sides of a rail joint, a round hole of one bar will align with an elliptical hole in the opposite bar, so that the bars may be bolted together by bolts having elliptical heads as are commonly used for this purpose. In reshaping worn splice bars it is necessary to restore the bar to its original shape, so that the head and flange wearing surfaces conform to the original design, and it is important to prevent the distortion of the bolt holes; and, where the bolt holes of the original bar have been unduly worn out of shape, it is necessary to compress the metal of the bar around the holes, to such extent that the original size and shape of the holes will be restored.

According to my invention, the angle or splice bars are advantageously reshaped by compressing them within vertically movable die members. The

bars are supported in the lower die member in an inclined position with respect to the horizontal plane, that is, the major axis of the bar is not perpendicular to the direction of movement of the movable die. This permits of a ready distribution of the metal from the head and flange portions of the bar without undue thinning of the web portion so as to materially weaken the reformed bar. Furthermore, it permits of the use of the novel means for restraining the flow of metal into the bolt openings, so that their original size and shape may be maintained.

According to my invention, the splice bars are preferably reshaped by a single forging operation, and in the present instance upper and lower die holders 10 and 11 respectively, of suitable forging presses, as for instance, a hydraulic ram, air or steam hammer or power press, are adapted to receive upper and lower dies 12 and 13, respectively. The lower, or bottom die 13, is preferably stationary and is formed with surfaces to shape accurately the head-wearing and flange-wearing surface of the splice bar, the shape and mounting of the die 13 being such that the splice bar is supported thereon at an angle to the horizontal plane, that is, the bars are so supported during the reshaping forging operation, that the axis of the bolt holes is inclined with respect to the vertical axis of the press, and to the direction of movement of the upper movable die.

In order to maintain the original size and shape of the bolt holes during the reshaping operation, or to restore enlarged holes to their original size and shape, as the case may be, I form each die member 12 and 13 with bolt hole shaping lugs 14 and 15, respectively, the lug 15 being fixed in the lower die 13 in any suitable manner, so that a portion of it projects from the bridge portion 14' of the bottom die, and at an angle to the direction of vertical movement of the upper movable die. Advantageously the lower die is formed in a number of sections for convenience in changing the dies or replacing the worn parts thereof. Thus, when the worn angle bar is in place in the lower die the lugs 15 extend through the transverse bolt holes of the bar.

The lugs 14 are suitably secured in the upper movable die, and project downwardly therefrom and at an angle to the vertical axis of the die, so that when the upper die is lowered upon the bar to press it, the lugs 14 will enter the upper partly open ends of the bolt holes, and being complementary to the lug 15 will accurately maintain the bolt holes to proper size and shape during the reforming of the bar. The adjoining

faces 17 of the respective pairs of lugs 14 and 15 are cut obliquely to the axis of the lugs or at such an angle as to permit relative vertical movement of the lugs and dies and also permit the lug 14 to enter into the upper partially open end of the bolt hole.

As stated above, the bolt holes of splice bars are conventionally of alternately elliptical and circular shape, and according to my improved 10 apparatus for reforming bars, alternate lugs are preferably elliptical and circular, (as shown in Fig. 1), so that the original size, shape and arrangement of the bolt holes may be retained.

By the above described means accuracy in the 15 size and shape of the bolt holes is maintained during the reforming and as the lower die member is accurately shaped to conform to the shape of its desired bar, so that when the heated bar is subjected to pressure between the dies, the metal 20 of the bar will be forced into the lower die to fill out the worn parts of the bar and thus restore it to its original usefulness.

The upper die member is provided with adjustable stops 18, adapted to strike the upper face of 25 the die holder 11. In this way a predetermined stroke is maintained. Thus, the method may be practiced in a hydraulic, air, or steam press as well as a power press.

After the bar has been reshaped, and the upper die is being raised, the bar will adhere to the lower die, as the angularly disposed bolt hold forming lugs 15 will prevent movement of the bar vertically with the upper die. As the bar chills rapidly, it must be readily and quickly 35 stripped from the lower die, and accordingly, I provide stripping mechanism for quickly removing the bar from the lower die in a direction parallel to the axis of the lugs 15. In the present embodiment of the invention, the stripping mechanism 40 comprises one or more stripping pins 19 movably mounted in the lower die being positioned therein parallel to the axis of the lugs 15. When in lowered position, the stripping pins 19 constitute parts of the lower die, their upper faces 45 being shaped to conform to the shaping of the lower die. The lower portions of the pins 19 have downwardly projecting reduced stems 20 extending downwardly through the lower die holder and into side opening recesses 21, wherein they may 50 be suitably connected to an actuating bar 22, common to all of the pins when more than one pin is used. Thus, by actuation of the bar 22, the stripping pins 19 will be raised, stripping the bar from the movable die 13 and lugs 15.

55 By reforging or reshaping the bars by pressure applied obliquely to the major axis of the bar, as described above, the convergent head and flange wearing faces of the bar may be readily restored to their original shape by the direct displacement of metal from the heavier head and flange sections of the bar, and without material compression and distortion of the web of the bar as in prior methods. The displacement of the metal is slightly obliquely to, but almost parallel to the plane of the worn rail head and flange 60 wearing surfaces of the bar (see Fig. 3) so that the bars may be satisfactorily reconditioned with a minimum of pressure.

The above method may be satisfactorily oper-

ated in a hydraulic or steam press as well as a power press, by the use of stop members 18 to limit the stroke of the movable die. In using a hydraulic press set to a predetermined pressure the extent of wear of the angle bar determines 80 the stroke of the press except that the adjustable stops 18 prevent damaging contact of the tempered dies and hole-forming lugs. Thus no previous assorting of the bars is required.

Advantages of my invention reside in the 85 economical manner in which worn angle bars or splice bars may be reshaped and restored to their usefulness as well as the simplicity and sturdiness of the apparatus, permitting rapid and continuous operation. Furthermore, according 90 to the invention, worn splice bars may be reshaped to their original or other sizes as desired, and may also be reformed in different shapes as desired.

I claim:

1. An apparatus for reforming worn splice bars having convergent rail head and rail flange wearing faces comprising relatively movable die members, one of said die members being longitudinally channelled to receive and support the bar obliquely relative to the direction of movement of said movable die members, so that the rail head and rail flange wearing faces of the bar are disposed substantially parallel to the direction of movement of said die members, and means for 105 applying pressure of the movable die members to the head and flange portions of the bar to cause the metal thereof to be displaced directly toward the rail and flange wearing faces thereof, and without material compression of the intermediate web portion of the bar, and adjustable stop members on one of the die members adapted to engage the other die member and limit movement of the die members toward each other.

2. An apparatus for reforming worn splice bars 110 having convergent rail head and rail flange wearing faces comprising relatively movable die members, one of said die members being longitudinally channelled to receive and support the bar obliquely relative to the direction of movement of 115 said movable die members, so that the rail head and rail flange wearing faces of the bar are disposed substantially parallel to the direction of movement of said die members, and means for applying pressure of the movable die members to the head and flange portions of the bar to cause the metal thereof to be displaced directly toward the rail and flange wearing faces thereof, and without material compression of the intermediate web portion of the bar.

3. Apparatus for reforming worn splice bars 120 having transversely extending bolt holes therein according to claim 2 characterized by means engaging in the bolt holes of the bar to maintain the original size of the holes during reforming 125 and also serving to prevent the bar adhering to the movable die.

4. Apparatus for reforming worn splice bars according to claim 2 further characterized by the provision of stripping means movable through the 140 supporting die and adapted to strip the bar therefrom as the movable die disengages the work.

OLAF J. NYBERG.
